UNITED STATES PATENT OFFICE.

ETIENNE PROST, OF MARSEILLE, FRANCE, ASSIGNOR TO HENRI GIRARD, OF MARSEILLE, FRANCE.

ROUNABOUT AFFECTING THE SHAPE OF A GIANT TOP.

Application filed February 7, 1923. Serial No. 617,523.

To all whom it may concern:

Be it known that I, ETIENNE PROST, citizen of the Republic of France residing at 1 Boulevard Pascal, Marseille, France, have 5 invented certain new and useful Improvements in Roundabouts Affecting the Shape of a Giant Top, of which the following is a specification.

This invention relates to a roundabout for 10 pleasure shows, the roundabout affecting the shape of a giant top revolving about its main axis and rolling with its marginal edge upon a track, imitating the bearing of a spinning top which is about to stop 15 revolving.

The object of the invention is to offer to 20 the passengers new sensations in absolute safety against all accidents even if voluntarily provoked, and also to provide a complete structure for this purpose which is light, easy to erect and to dismount, to operate and to transport whilst being absolutely safe against all accidents.

Besides the peculiar characteristic shape 25 of the roundabout looking like a giant spinning top, the whole presents the following features:

The track upon which the roundabout is 30 adapted to roll is not flat, but is formed with an undulated profile resembling the profile of a toboggan or coaster.

At one point in the track a suitable depression is provided, said depression serving to bring the top to a dead stop after the 35 speed of the roundabout is sufficiently reduced; the roundabout being brought to rest opposite the station and with its platform in almost a horizontal position.

The transmission of motion from the 40 driving axis is effected by means of a worm which drives a toothed wheel fixed on the one end of an articulated shaft which is fixed at its other end to the middle of the platform.

The seats are rigidly connected to the platform as it would be dangerous to allow them to turn freely in view of the relative inclination of the platform.

This invention is more particularly described with reference to the accompanying drawings, in which an example of the preferred construction is shown.

Fig. 1 is a perspective view of the whole device;

Fig. 2 is a plan view of the device with 55 the hood N removed;

Fig. 3 is an elevation with one-half in section, of the contrivance, the platform being horizontal or nearly so.

Fig. 4 is a plan view of a seat for two 60 persons;

Fig. 5 is a section taken on the line 5—5 of Fig. 4.

As shown in the drawings, the track is undulated on its upper edge and the platform 65 is covered by a shelter; the seats are rigidly connected to the platform and the passenger receives the sum of the sensations due to the inclined rotation and to the rise and fall.

In the basement A (Figs. 1, 2 and 3) is 70 the electric motor B, connected by the worm gear C to the toothed wheel D fixed upon the vertical portion E of the articulated shaft, said portion E transmitting the whole strain and rolling in the bronze bearing E' 75 provided with a steel base; this shaft carries at its upper extremity the fork F receiving and maintaining the movable eye piece G on the lower end of shaft part H which with the shaft E forms the articulated shaft. 80 This shaft H is the principal part upon which is placed and fixed at the one end the inverted conical casing I receiving the lower portion of the metal structure J, and at the other end the circular platform K also connected to the structure J.

The peripheral edge of the platform K is provided with a rounded off piece of lining L contacting with the track M (Figs. 1 and 2) upon which in rolling the giant top 90 travels due to the action of the driving shaft E on shaft H articulated thereto.

Above the platform K a hood N of cloth or the like is disposed, or any other suitable shelter, affecting a decorative shape, for the 95 seats O disposed on the platform is provided.

The seats O (Figs. 4 and 5), the number of which may vary at will, are cylindrical in form and are upholstered, and accommodate two passengers comfortably. A door P gives access to the seats and this door may be locked from the outside in any known way. For safety's sake a bar Q, shown in dotted lines in Figs. 4 and 5 may keep the 100 passengers on their seats which are fixed on the platform K by means of the bolts R. The upper surface of the platform is pro- 105

vided with wooden slats S disposed so as to afford a foot hold if it is necessary to move about the platform when in an inclined position. A yielding railing S' is provided on the platform K at its periphery.

5 A slight depression of the track, shown at T, suffices to finally stop and retain the giant top in front of the terrace U during the time required for getting the passengers in and out. The controlling apparatus of motor B may be disposed either on an extension of the terrace U or otherwise near to the ground and between the two flights of steps V, V'.

10 15 The equipment of the roundabout is completed by any known arrangement of lamps X turning with the platform.

15 20 The angles of inclination (maximum and minimum) of the giant spinning top are calculated so as never to displace the centre of gravity to a degree capable of compromising the stability of the whole and thus causing the possibility of upsetting.

Any suitable brake or safety stop consisting of a known locking device (not shown in the drawings) grants the immobility of the giant top during halts, and even in this position the platform is inclined.

25 30 In order to ensure smooth running and to economize motive power, ball bearings are disposed in all principal friction points.

Naturally the revolving speed of the giant top varies during every single trip.

30 35 I declare that what I claim as my invention is:—

An amusement apparatus comprising a roundabout shaped like a giant top, an entrance and exit platform, an undulating track formed with a depression for receiving the roundabout and facilitating the stoppage thereof alongside said platform; and a peripheral edge on the roundabout for engaging and rolling upon the said track.

40 In testimony whereof I affix my signature.

ETIENNE PROST.
